UNITED STATES PATENT OFFICE.

HUGO LENTZ, OF HALENSEE, NEAR BERLIN, GERMANY.

COMPOUND STEAM-ENGINE.

1,118,662.

Specification of Letters Patent.

Patented Nov. 24, 1914.

Application filed September 30, 1914. Serial No. 864,232.

To all whom it may concern:

Be it known that I, HUGO LENTZ, a citizen of the German Empire, and residing at Halensee, near Berlin, Germany, have invented certain new and useful Improvements in Compound Steam-Engines, of which the following is a specification.

My invention relates to compound steam engines.

10 The invention is particularly useful in connection with compound engines of the Woolf type having steam distribution chests arranged separate from one another at the cylinder ends, each of which contains valves 15 which control the flow of steam to and from the cylinders, all the valves being actuated by a lay shaft disposed transversely of the cylinders.

In the type of engine described the valve-20 guides and the lay shaft casing were heretofore cast in one piece with the two cylinders. In order to be able to make this casting several pattern boxes were required and it was also necessary to insert a number 25 of cores. This rendered not only the manufacture of the pattern but also the casting of such cylinder and its subsequent machining troublesome and expensive.

One of the objects of my invention is to 30 arrange and construct the valve operating mechanism in a durable and efficient manner.

Another object of my invention is to obviate the difficulties which have arisen from 35 having the valve stem guides and the lay shaft casing cast in one piece with the two cylinders. To this end I make the casing of the lay shaft and also the valve-stem guides as separate parts distinct from the cylinder 40 casting proper. The steam chests mounted on the ends of the cylinder and also the cylinder itself then have an exceedingly simple and smooth shape, so that such a compound steam engine cylinder can be cast with a 45 few pattern boxes. This advantage is felt particularly in the case of compound engines of the Woolf type having an intermediate valve between each two cylinders, because on account of the intermediate valve 50 the two cylinders must be cast in one piece. In addition, the machining of such a cylinder is very simple because all the holes in it are located parallel to one another. Further, the separation of the lay shaft casing 55 and the valve-stem guides from the cylinder casting proper renders it possible not only

to place the valves as compactly and close together as possible on the cylinders, for the purpose of procuring the shortest path for the steam, but also to make the lay shaft not materially longer than the diameter of the low-pressure cylinder.

To these ends my invention consists in the construction, arrangement and combination of parts described hereinafter and pointed out in the claims.

Two illustrative embodiments of my invention are represented by way of example in the accompanying drawings, wherein:

Figures 1 to 3 relate to a locomotive engine of the type described, Fig. 1 being a cross-section through the two cylinders taken on the line 1—1 in Fig. 2. Fig. 2 a longitudinal section taken on the bent line 2—2 in Fig. 1, and Fig. 3 a cross-section taken on the line 3—3 in Fig. 2; Figs. 4 and 5 relate to a marine engine of the type described, the cylinder covers having been removed, Fig. 4 being a cross-section through the cylinders of the engine, the upper half 70 being a section taken on the line 4—4'—4 and the lower half a section taken on the line 4—4''—4 in Fig. 5, and Fig. 5 is a section taken on the line 5—5 in Fig. 4.

Referring firstly to Figs. 1 to 3, at each 80 end of the high-pressure cylinder *a* and of the low-pressure *b* is arranged a steam distributing chest *c* common to the two cylinders, and the steam enters at *g* into and issues at *h* out of this chest. By means of 85 suitably arranged walls in these steam chests 90 passages are formed through which the steam can pass from the admission branch *g* through the inlet valve *d* into the high-pressure cylinder *a*, from this through the intermediate valve *e* into the low-pressure 95 cylinder *b* and from this through the exhaust valve *f* into the exhaust branch *h*.

The valves *d*, *e* and *f* are actuated by the lay shaft *l* located in the bore *m* in the casing *i*. This casing *i* is a member separate from the cylinders, as also are the valve-stem guides which are formed as separate tubular boxes or bushes *k* in which are mounted the valve stems *r* whose ends coact 100 with cams milled in the shaft *l*. These boxes *k* are introduced through the ends of the valves into the casing *i* in such manner that the latter is held by the boxes and requires to be screwed to the projections *a'*, *b'* of the 105 cylinder with only a small surface contacting with it. In such a construction that part

of the cylinder casting which is most difficult to mold and to cast is done away with, namely the transverse lay shaft casing, which has heretofore been cast with the cylinder, and the valve-stem guides disposed longitudinally thereof. An exceedingly simple cylinder casting results which can be made with only a few patterns and readily admits of manufacture on duplication methods. In addition, it is possible to place the valves mounted in the distributing chests as near as possible to the cylinders, which arrangement is particularly favored, on the one hand, by the large exhaust valve 15 being located in the free space between the high and low pressure cylinders and, on the other hand, by the lay shaft or the lay shaft casing *i* being not substantially longer than the diameter of the low-pressure cylinder, 20 so that it can be better adapted to the cylinders and accommodated close above the high-pressure cylinder in the box-shaped space which is bounded below by the high-pressure cylinder *a*, on each side by the two 25 distributing chests *c* and on the end by the low-pressure cylinder *b*. This arrangement nevertheless admits of the short lay shaft being conveniently removed laterally toward the high-pressure side. This is exceedingly 30 advantageous in locomotive engines because in these the high-pressure cylinder is generally located outside or can be readily placed there, and the herein-described construction assures ready accessibility of the 35 lay shaft, particularly from this side, and a simple drive of the same. The valves and valve stems can also be readily removed because the covers of the valve chests are completely exposed.

Owing to the compact construction enabled according to my invention in combination with the short steam passages and the short bores, and owing to the arrangement of the members driving the valves in casings made separate from the cylinders the 45 radiating surfaces are reduced to a minimum inasmuch as the valve-stem guides made separate from the cylinder castings are completely exposed and therefore can heat only 50 little and can transmit only little heat.

The same advantages can be obtained in marine engines having vertical cylinders as will be understood from Figs. 4 and 5 in which those parts which correspond to like 55 parts in the embodiment described above are designated by like reference letters. The only difference between this marine engine and the construction described above is that the lay shaft casing passes transversely 60 through the free space between the high-pressure cylinder *a* and the low-pressure cylinder *b* separate therefrom, and is attached in suitable manner to the low-pressure cylinder *b*. The lay shaft casing *i* is connected 65 in the manner described above by the valve-

stem boxes *k* with the distributing chests *c* which in this case constitute the sole mechanical connection of the two cylinders. The valve stems are located parallel to the cylinders in a plane located at right angles 70 to the middle plane common to the two cylinders. This construction also assures a simple cylinder casting and results in short steam passages and a short lay shaft casing which need not be materially longer than 75 the diameter of the low-pressure cylinder. The entire valve gear is also readily accessible because both the valve covers and also the lay shaft are located between the feet 80 *p* of the cylinders.

I claim:

1. In a compound steam engine the combination of a plurality of cylinders having connecting end members provided with passages for the flow of steam from one cylinder to the other, valves controlling the flow of steam through said passages, valve spindles disposed longitudinally of the cylinders for operating said valves, a lay shaft disposed transversely of the cylinders intermediate the ends thereof and having means for operating the spindles, and a supporting casing for the lay shaft formed separate from the cylinders and detachably supported therefrom.

2. In a compound steam engine the combination of a plurality of cylinders having end members each provided with passages for the flow of steam from one cylinder to the other, valves located in said passages and controlling the flow of steam through the same, reciprocating valve spindles extending from the valves longitudinally of the cylinders toward the middle thereof, a lay shaft disposed transversely of the spindles at the 105 adjacent ends thereof and having means for operating the same, a supporting casing for the lay shaft formed separate from the cylinders, and spindle guides formed separate 110 from the cylinders and from said supporting casing and detachably securing the latter to said end members of the cylinders.

3. In a compound steam engine the combination of a plurality of cylinders having common end members connecting the adjacent ends of the cylinders and provided with a plurality of passages for the flow of steam from one cylinder to the other, a plurality of valved ports through which said passages communicate, said ports being all located 120 substantially to one side of the low pressure cylinder and above the high pressure cylinder, valves controlling said ports, valve spindles extending from the valves longitudinally of the cylinders and toward the middle 125 of the same, and a lay shaft disposed transversely of the high pressure cylinder to one side thereof adjacent the inner ends of the valve spindles and having means for operating 130 said spindles.

4. In a compound steam engine the combination of a plurality of cylinders having common end members connecting the adjacent ends of the cylinders and provided with 5 a plurality of passages for the flow of steam from one cylinder to the other, a plurality of valved ports through which said passages communicate, said ports being all located substantially to one side of the low pressure cylinder and above the high pressure cylinder, valves controlling said ports, valve spindles extending from the valves longitudinally of the cylinders and toward the middle of the same, and a lay shaft disposed transversely of the high pressure cylinder to one side 30 thereof adjacent the inner ends of the valve spindles and having means for operating said spindles, said lay shaft extending toward the low pressure cylinder, a supporting frame for the lay shaft formed separate 35 from the cylinder and its end members, separate tubular guides for the different spindles telescoping at their ends with the end members of the cylinders and with the lay shaft casing. 40
- 10 cylinder and above the high pressure cylinder, valve controlling said ports, valve spindles extending from the valves longitudinally of the cylinders and toward the middle of the same, a lay shaft disposed transversely 15 of the high pressure cylinder to one side thereof adjacent the inner ends of the valve spindles and having means for operating said spindles, and separate supporting and guiding means for said lay shafts and for 20 the valve spindles.

5. In a compound steam engine the combination of a plurality of cylinders having common end members connecting the adjacent ends of the cylinders and provided with 25 a plurality of passages for the flow of steam from one cylinder to the other, a plurality of

valved ports through which said passages communicate, said ports being all located substantially to one side of the low pressure cylinder and above the high pressure cylinder, valves controlling said ports, valve spindles extending from the valves longitudinally of the cylinders and toward the middle of the same, and a lay shaft disposed transversely of the high pressure cylinder to one side 35 thereof adjacent the inner ends of the valve spindles and having means for operating said spindles, said lay shaft extending toward the low pressure cylinder, a supporting frame for the lay shaft formed separate 40 from the cylinder and its end members, separate tubular guides for the different spindles telescoping at their ends with the end members of the cylinders and with the lay shaft casing. 45

In testimony whereof, I affix my signature in the presence of two witnesses.

HUGO LENTZ.
